UNITED STATES PATENT OFFICE

125,274

DESIGN FOR A TOY ROTARY UNIT

Martha Kiefer, Chicago, Ill.

Application June 19, 1940, Serial No. 93,093

Term of patent 7 years

To all whom it may concern:

Be it known that I, Martha Kiefer, a citizen of the United States, residing at Chicago, in the county of Cook and State of Illinois, have invented a new, original, and ornamental Design for a Toy Rotary Unit, of which the following is a specification, reference being had to the accompanying drawing, forming part thereof.

In the drawing:

Fig. 1 is a side elevational view of a toy rotary unit showing my new design.

Fig. 2 is an edge elevational view of the toy shown in Fig. 1.

I claim:

The ornamental design for a toy rotary unit, substantially as shown.

MARTHA KIEFER.
